SPLITTING MACHINE

Charles E. Hood, Lynn, Mass., assignor to United Shoe Machinery Corporation, Flemington, N. J., a corporation of New Jersey

Application November 18, 1940, Serial No. 366,063

35 Claims. (Cl. 12—17)

This invention relates to splitting machines and is herein illustrated as embodied in a machine having a matrix into which a portion of the work is forced during the splitting operation.

In the manufacture of a certain type of shoe, a sole-shaped blank is split into an outsole having on its forepart a projection and an insole having a correspondingly located complementary opening, which may or may not extend through the insole. Machines for performing this and similar operations commonly comprise a knife, a roll having a cylindrical portion and a matrix, and a second roll which cooperates with the matrix roll to advance the work to the knife and to force a portion of the moving work into the matrix.

According to one feature of the present invention, a series of presser fingers are provided which press a part of the moving work against the cylindrical portion of the matrix roll and another part of the work into the matrix. Preferably the finger or fingers which cooperate with the matrix are caused to press against the work with greater force than the others; and since these fingers are more difficult to depress and would tend to interfere with the entrance of the leading end of a piece of work between the rolls, these fingers are first depressed to permit ready entrance of the leading end of the work and then released in time to act upon that portion of the moving work which is pressed into the matrix.

In accordance with another feature of the invention, a single matrix is provided which is adapted for use with either right or left blanks, means being provided for ensuring that right blanks shall be presented to the matrix while in one angular position and left blanks while in another.

In order to speed up the operation of the machine, there is provided a magazine for stacks of blanks and means for feeding the blanks in succession to the mechanism including the matrix for operating upon the blanks. The blanks of any given stack are selected so that they are all of the same length, but the blanks of different stacks may be of different lengths. According to another feature of the invention, the front wall of the magazine is adjustable toward and from the mechanism for operating upon the blanks so as to vary the distance of the leading ends of the blanks of the stack from the mechanism for operating upon them, and the feeding means is adapted to feed all blanks the same distance, irrespective of their lengths. Thus the position of

the front wall determines the locality on each blank which shall be engaged by the matrix.

These and other features of the invention, including certain details of construction and combinations of parts will be described as embodied in an illustrated machine and pointed out in the appended claims.

Referring to the accompanying drawings,

Fig. 1 is a side elevation of a machine in which the present invention is embodied, the receptacles to receive the soles and insoles having been omitted;

Fig. 2 is a plan of the machine;

Fig. 3 is a vertical longitudinal section of the machine, the mechanism for distributing the soles and insoles having been omitted;

Fig. 4 is a vertical section showing the driving mechanism;

Fig. 5 is a section on the line V—V of Fig. 3 showing the connection between the driving mechanism and the mechanism for feeding blanks from the stack;

Fig. 6 is a detail, partly in plan and partly in section, showing the mounting of the matrix roll;

Fig. 7 is a detail, principally in section, of the mechanism for adjusting the matrix roll;

Fig. 8 is a rear elevation of the magazine for the stack of blanks;

Fig. 9 is a side elevation of the mechanism for adjusting the side walls of the magazine in unison in the same direction, certain parts being shown in section;

Fig. 10 is a view, taken from above, of the parts shown in Fig. 9;

Fig. 11 is a detail on an enlarged scale, partly in section and partly in elevation, showing more particularly the relation of the presser fingers to the knife and rolls;

Fig. 12 is a plan view of a modified mounting of the matrix roll; and

Figs. 13 and 14 are perspectives respectively of the insole and the sole which result from the operation of the machine upon a sole-shaped blank.

The purpose of the illustrated machine is to split a sole-shaped blank into an outsole 200 (Fig. 14) having a projection or island in its forepart, and an insole 300 (Fig. 13) having a correspondingly located complementary opening which may be merely a recess. To this end, stacks of sole blanks 100 (Fig. 3), each stack consisting of sole blanks of the same size, are placed in a magazine and fed one by one from the bottom of the stack to the splitting mechanism. Preferably, as will appear below, the members of the stack consisting of the longest sole blanks

are split first and then, in order, the members of the stacks of smaller blanks. The sole blanks are fed to the splitting mechanism, which includes a matrix and a knife, by a reciprocating pusher or feeder 11. The extent of reciprocation of this feeder is constant, but the location of its path of reciprocation may be varied to take care of sole blanks of different lengths. The magazine (Fig. 3) comprises side walls 13, 15, a back wall 17 V-shaped in cross section, and a front or stop wall 19. As will be described in detail hereinafter, the illustrated matrix, in the preferred embodiment, is a symmetrical one, the same matrix being used in splitting right or left sole blanks, and the position into which the front wall is adjusted determines the location of the island or projection on the outsole and the corresponding opening in the insole lengthwise of these two members.

The splitting mechanism to which the sole blanks are fed comprises a lower toothed feed roll 21, an upper roll 23 having in it a matrix 25, a series of main presser fingers, two of which are indicated at 26 and 526, respectively, a stationary knife 27, and a series of four auxiliary presser fingers 29. There are forty-six presser fingers in the main series. Of these, there are four like the finger 26, these being located in the middle of the series in position to cooperate with the matrix to distort a blank while it is being split. The lower or feed roll 21 is made up of spaced toothed disks between which stripper fingers on a stripper plate 31 extend. The four auxiliary presser fingers 29 are integral with a narrow plate, which is fastened to the underside of the stripper plate and are in line with the four middle presser fingers 26. From the splitting mechanism, the insoles slide down the upper face of the stripper plate 31 and are delivered into a receptacle, while the soles slide down a chute 33 and are delivered into another receptacle. The delivery mechanism, comprising rotary horizontal disks, one of which is shown in Fig. 2 will be described later.

The upper or matrix roll 23 is rotatably mounted in two aligned bent arms 33, 35, the arm 33 being shown in Fig. 3, and both arms being shown in Fig. 2. These arms are pivoted at their right-hand or rear ends about a fixed center 36 and have extending through their left-hand or forward ends a horizontal slidable shaft 37, sliding movement of which serves to adjust the matrix roll toward and from the feed roll.

Referring to Fig. 1, the left-hand end of the arm 35 is urged upwardly about its pivotal center 36 by a compression spring 39, which is seated in a socket in the frame of the machine and engages with its upper end a small disk, acted upon by a screw 41, said screw being threaded through a lug on the arm 35. The other arm 33 is urged upwardly by a spring, not shown, which is like the spring 39 and is mounted in a similar manner. These springs tend at all times to raise the matrix roll. The manner, in which sliding the shaft 37 adjusts the matrix roll down against the force of the springs, is shown in Fig. 7. The shaft 37 is slidable horizontally through the lower ends of the arms and through bores formed in parts 43, 45, which are rigid with the frame of the machine. Formed in the shaft are two grooves with inclined bottoms 47, 49, upon which heads of pins 51, 53 are slidable. Since the mountings of these two pins are alike, only one will be described in detail. The pin 51 extends up through a bore in a block 55, which is bolted

to the stationary part 43 and has an upward extension threaded on its outside. Upon this threaded extension is screwed a cap 57, the underside of which bears upon the top of the pin 51, a lock nut 59 being provided for locking the cap in adjusted position. The shaft 37 is urged at all times to the left by a compression spring 61, which bears at one end against a collar 63 fast to the shaft and at the other end against a washer, which in turn bears against the stationary part 45. A screw provided with a handhold 65, when turned in one direction, pulls the shaft 37 to the right and thereby lowers the matrix roll. When this screw is turned in the other direction, the spring 61 pushes the shaft to the left and raises the matrix roll. The adjusted position of the roll 23, that is its distance above the knife, is indicated by a pointer 64, and scale 66 (Fig. 2). The cap 57 and the corresponding cap 67 are adjusted to hold the lower enlarged ends of the pins 51, 53 against the inclined bottoms 47, 49 of the grooves in the shaft and ordinarily are not further adjustable. However, if the matrix roll is slightly nearer to the knife at one end than at the other, there is enough play in the various parts so that one of the caps 57, 67 may be screwed down farther so as to make the feed roll exactly parallel to the edge of the knife. The lower or feed roll 21 (Fig. 1) is mounted similarly to the matrix roll in bent arms, one of which is shown at 68, the arms being urged upwardly at all times by compression springs, one of which is shown at 70. The arms for the lower roll are prevented from swinging up far enough so that the roll will contact with the knife by stop screws, one of which is shown at 72. A slide rod, like the slide rod 37 for the matrix roll, may be pulled toward the observer or allowed to move away from the observer to adjust the feed roll up or down, a hand hold 74, like the hand hold 65, being provided for this purpose. By turning the hand hold 65, the upper roll may be adjusted substantially vertically into a given position and held from movement away from the knife. By turning the hand hold 74, the feed roll may be adjusted substantially vertically but is still permitted to be moved away from the knife by a sole blank as it passes between the rolls. The mounting of the rolls and the mechanism for adjusting them is similar to the mounting of the rolls and the adjusting mechanism in the machine of Patent No. 2,082,057, granted June 1, 1937 upon application filed in my name, except that in the patented machine the matrix roll is the lower roll and the feed roll is the upper roll.

Referring again to Fig. 3, the feed slide or pusher 11 is reciprocated, as will presently appear, by oscillating an arm 69 about a rod 71. This arm is connected by a link 73 to a bent lever 76, which swings about a stud 75 and carries at its outer end a small roll 77, said roll being received in a closed cam track 79 formed in a cam 65 which is fast to a countershaft 81. Rotation of this shaft, which thus oscillates the arm 69, also causes rotation of the rolls 21, 23 through gearing shown in Fig. 4. Fast to the shaft 81 is a gear 83, which meshes with a gear 85 on a shaft 87. Also fast to the shaft 87 is a gear 89 which drives a gear 91, fast to the shaft of the feed roll. The gear 89 also drives a gear 93, the axis of rotation of which is the axis about which the matrix roll is swung for adjustment, said gear 93 meshing with a gear 95 which is fast

to a shaft which drives the matrix roll. The construction described above is such that the blanks are fed to the rolls 21, 23 at the same speed as the rolls advance the blanks to the knife.

The countershaft 81 is driven from a continuously rotated pulley 97, which has formed in one side of it the hollow member of a friction clutch, the other conical member of which is indicated at 99. Fast to the countershaft 81 is a spiral gear 101 which meshes with a spiral worm 103 on a sleeve 105, said sleeve being located between portions of the frame and, with the aid of washers 107, is held from longitudinal movement. This sleeve 105 is fastened by screws, one of which is indicated at 109, to the right-hand hollow portion of a shaft 111 which is rotatably mounted in the frame, the left-hand solid end of this shaft carrying the pulley 97 which is rotatable relatively thereto. The right-hand end of the hollow hub of the conical member 99 of the clutch has projections which are received in slots in the left-hand end of the sleeve 105, to which the spiral worm is fast, so that the worm is rotated when the clutch is engaged. A compression spring 113 tends at all times to push the member 99 to the left to engage the clutch, but is held from doing this, in the position of parts shown, by a slender rod 115, having near its left-hand end a cross-pin 117 which passes through bores in the projections on the hub of the conical friction member 99, through the slender rod 115 and loosely through an enlarged bore in the sleeve 105. The right-hand end of the rod 115 passes loosely through a bore in the upper end of a bearing 118 pivotally held at the upper ends of two substantially upright links 119, both of which are shown in Fig. 2. A compression spring 121, which is stronger than the spring 113, pulls the rod 115, and with it the member 99 of the clutch, to the right when the links 119 are substantially upright, as shown. When, however, the links 119 are swung to the left through the small angle indicated by the dot-and-dash lines, the clutch is engaged yieldingly through the spring 113. The links 119 are fast at their lower ends to a small rock shaft 123, to which is fastened the lower end of an arm 125, said arm being in the position shown when the machine is at rest but being capable of being swung to the left by straightening two small toggle links 127, 129.

When the machine is stopped, it is desirable that the arm 69 (Fig. 3), which reciprocates the sole blank pusher or feeder 11, be always in its retracted position, as shown. To this end, the mechanism shown best in Figs. 1 and 3 is provided. Referring to Fig. 1, the machine is started by swinging an arm 131 to the right until it contacts with a stop 133. When the arm 131 is swung to the right about the rod 71, about which the feed arm 69 is also pivoted, a small cam 137 integral with the starting and stopping arm 131 engages a small roll 139 on the lower end of a small arm 141 and swings the arm to the right. The hub of this small arm is pinned to a small rock shaft 143, which extends through the frame and out on the other side of the machine. Referring now to Fig. 3, wherein the other end of the rock-shaft 143 is shown in cross section, and to Fig. 5, there is also fast to this rock-shaft the hub of a small casing 145, having a small roll 147 held up by a spring 149 against the underside of a projection 148, which is integral with the hub of the feed arm 69.

When the rock-shaft 143 is rocked counterclockwise (Fig. 3) the casing 145 is swung to the right into contact with a stop screw 149, the small roll 147 being thus swung from beneath the projection 148 so as to free the feed-arm 69. The toggle member 129, referred to above, also has its hub fast to the rock-shaft 143; and when the casing 145 is swung to the right the toggle member 129 is swung to the left sufficient-
5 ly to straighten the toggle mechanism and to move its knuckle past dead center. A tension spring 151 fast at its upper end to the frame of the machine and at its lower end to a small arm 153, the hub of which is fast to the rock-shaft 143, tends to swing the casing 145 to the left, but is prevented from doing so by reason of the fact that the knuckle of the toggle has been moved past dead center. Straightening the toggle mechanism 127, 129, as has been explained, 10 swings the link 125 to the right, as viewed in Fig. 3 (to the left as viewed in Fig. 4) and starts the machine. When the start-and-stop lever 131 (Fig. 1) is swung back to its stop position, the spring 151 (Fig. 3) swings the casing 145 to the left; and the small roll 147, as soon as 15 it is permitted to do so, moves into the position shown beneath the projection of the feed arm 69. Thus, the machine always stops in the position shown, with the pusher or feeder 11 retracted and the matrix roll 23 with its matrix in the angular position shown, this position, it being understood, being correlated with the retracted position of the pusher 11 so that, when sole blanks have been placed in the magazine and the machine has been started, the islands on the soles and the corresponding openings in the insoles will be properly located, assuming that the front or stop wall 19 of the magazine has been 20 adjusted into proper position.

40 The matrix roll is mounted, as shown in Fig. 6, for ready removal and replacement so that, for example, a roll having a different matrix may be substituted. The hub of the gear 95, which drives the matrix roll, is pinned to one end of a short shaft 155, the other end of which is enlarged and has a wide straight-sided groove 157 passing diametrically through it. The shaft 155 is rotatably mounted in the upper part of the arm 33. From the bottom of the groove 157 a bore 159 extends into the center of the shaft and has driven into one wall a small pin 161. The roll-shaft 163, having in its left-hand end a spiral groove 165 to receive the pin, is slidably and rotatably mounted in the other arm 35 and has a collar 166 near its right-hand end, the extreme right-hand end being knurled. The matrix roll 23 is just long enough to fit in between the enlarged end of the short shaft 155 and the adjacent face of the arm 35, and has a projection 169 which is a slide fit in the groove 157. To put the roll in place, the shaft 163 is pulled to the right until its left-hand end is in the arm 35; the roll is slid vertically into place, and then the shaft 163 is pushed to the left and rotated 45 to cause the groove 165 to receive the small pin 161. A collar 166 may be provided, if desired, which contacts with the arm 35. It has been explained that the machine comes to rest with the parts in the positions shown in Fig. 3, and it will be noted that the projection 169 on the matrix roll is substantially vertical at that time, so that the matrix roll may readily be removed and replaced.

46 Referring to Figs. 2, 3 and 8, the side walls 13, 15 of the magazine, which are adjustable

simultaneously toward and from each other as well as in unison crosswise of the machine, and the front wall 19 which is adjustable lengthwise of the machine as well as up and down, are carried indirectly by spaced upright stationary plates 171, 173. The rear wall 17, which is V-shaped in cross section, is slidably adjustable, as will be described later, along a bar, the forward end of which forms part of the bottom of the magazine. A plate 177 (Figs. 2 and 8) is fastened by small screws 179 to the side wall 13, said plate carrying, near the vertical middle of its rear portion, a horizontal rod 176 which is slideable through a bore in the stationary plate 173. At its upper forward end the plate 177 has an eye which is fastened to a cross-rod 181, said cross-rod being slideable in the stationary plates 171, 173. A coil spring 183, which bears at one end against the stationary plate 171 and at the other against the eye on the plate 177, tends at all times to move said plate, the side wall 13 and the slideable cross-rod 181 in a direction to move the side wall 13 outwardly away from the central longitudinal vertical plane of the machine, this movement being limited by contact of the head of one of the screws 179 with the stationary plate 173. The other side wall 15 is similarly mounted. It has fastened to it a plate 185, carrying near the vertical middle of the rear portion a horizontal rod 187 which is slideable through a bore in the stationary plate 171. At its lower forward end the plate 185 has an eye which is fastened to a slideable cross-rod 189, located directly below the cross-rod 181 and having on it a coiled compression spring 191 like the coiled compression spring 183 of the upper cross-rod 181. These two coiled compression springs tend to move the cross-rods in opposite directions and thereby to move the side walls 13, 15 in unison away from each other.

A stack of sole blanks is placed in the magazine and then, with his thumb and fingers, the operator moves the side walls 13, 15 toward each other until the walls contact respectively, with opposite sides of the stack, as shown in Figs. 2 and 8. When the operator thus moves the side walls toward each other, they remain in the position to which they were moved, being locked in such position by a small Horton clutch, presently to be described, which locks the slideable cross-rods 181, 189 in adjusted position. The two slide-rods 181, 189 are connected at their left-hand ends (Fig. 8) by a member 193 having its opposite ends forked. There is at each end of the member 193 a double fork, that is, a fork to receive the flattened end of one or the other of the slide-rods 181, 189, and a fork at right angles to the first-named fork. The flattened end of the slide-rod 181 is received in one fork while, slideable in that fork which is at right angles to the one which received the flattened end of the shaft, are two square blocks, one of which is shown at 195, said blocks being swiveled to the slide-rod 181 about a pin 197. The lower slide-rod 189 is attached in the same manner to the lower double fork on the member 193. Consequently, when the side walls 13, 15 are adjusted toward each other, the member 193 is rocked clockwise, as viewed in the figure, about a stud 199. The member 193 has integral with it the circular cup-shaped member 201 of a Horton clutch, which prevents the member 193 from rotating counterclockwise and, therefore, holds the side walls 13, 15 in adjusted positions. When it is desired to release the Horton clutch, a trig-

ger 203 is swung slightly to the right, whereupon the side walls 13, 15 are moved by the springs 183, 191 to their extreme separated positions. Thus, when a stack of sole blanks has been placed in the magazine and the side walls 13, 15 moved toward each other until they engage the sides of the stack, they remain substantially where put. After the sole blanks have been split, the trigger 203 is manipulated to cause the side walls to separate preparatory to having another stack of blanks placed in the magazine. It is sometimes desirable to move the side walls 13, 15 in unison in the same direction, either to one side or the other, so as to locate properly the island on the sole and the complementary opening in the insole widthwise of these two members respectively. To this end, the casting 205 (Fig. 1), upon which the double-ended forked member 193 and the Horton clutch 201 are mounted, is slideably mounted on two small horizontal rods 207, 209 for adjustment crosswise of the machine, it being understood that adjustment of the forked member 193 bodily to the right or left (Fig. 8) adjusts the slide-rods 181, 189 in unison in the same direction crosswise of the machine and, with them, the side plates 13, 15 of the magazine. To this end (Figs. 9 and 10), the casting 205 has a vertical bore in which a rotatable stud 211 is slideable to a very slight extent, said stud having at its lower end a head which limits upward sliding movement, and at its upper end a small flattened projection 213, said projection being received between and pivoted to the branches of a fork at one end of an operating lever 219. This lever has in it a comparatively large vertical opening extending from opposite sides of which are two pins 221, 223 having rotatable on them small blocks 225, 227. These blocks are received respectively in two horizontal grooves in the hub of the conical member 229 of a friction lock. The hub of the conical member 229 is vertically slideable on the stem 235 of a hollow stationary conical member 237, the lower end of said stem passing through a bore in a stationary part of the machine and being held in place by a nut 239. A spring 233 normally holds the conical member 229 in engagement with the hollow conical member 237 and also holds the lever 219 swung up slightly about its pivotal connection with the stud 211. In the position of the parts shown, the lever 219 is held in a given angular position about the axis of the stem 235; and consequently the locking members 229, 237 hold the casting 205 in adjusted horizontal position. When, now, it is desired to change the adjusted horizontal position of the casting, so as to move the side walls 13, 15 of the magazine in unison in the same direction, the left-hand end of the lever 219 is depressed slightly so as to disengage the conical member 229 from the hollow conical member 237; and then the lever 219 is swung in a horizontal path about the axis of the stem 235. The extent to which the lever 219 can be swung horizontally is limited by contact of a small pin 220 with one or the other branch of a V-shaped fork at the right-hand end of a bar 222. This bar is slideably adjustable longitudinally of the machine so as to vary the extent to which the lever 219 may be swung in a horizontal path. A clamping block operated by a thumb screw 226 holds the bar 222 in adjusted position.

The front or stop wall of the magazine, which

consists of the upright bar 19, is mounted for adjustment longitudinally of the machine toward and from the knife and rolls, and for vertical adjustment. The adjustment longitudinally of the machine is for the purpose of locating properly that portion of the cut of the knife which, when the matrix comes into operation, forms the island on the sole and the complementary opening in the insole. For long sole blanks, for example, the stop wall 19 will be adjusted into a position nearer to the matrix roll, and for short soles into a position farther from said roll. In the preferred illustrated construction, the matrix is a symmetrical matrix, one matrix serving for the splitting of all sole blanks including both rights and lefts. A symmetrical matrix, it will be understood, is a matrix which can be divided into two symmetrical portions by a plane which is parallel to the direction in which the work is advanced to the knife, in the illustrated construction by a plane which is at right angles to the axis of the matrix roll. As will appear later, the rear wall 17 of the magazine is adjusted crosswise of the machine in one direction or the other, according to whether the stack of blanks to be split is composed of rights or lefts. The blanks are placed in the magazine with their grain sides up. In Fig. 2, a stack of right sole blanks is being held in proper position, the front wall 19 being in position longitudinally of the machine to ensure that the matrix shall come into play at the correct distance from the toe ends of the blanks, and the rear wall 17 being in position crosswise of the machine for right sole blanks. The adjustment of the wall 19 up and down is to locate the lower end of the wall above the flat bottom of the magazine a distance which will permit only one sole blank at a time to be fed beneath it to the splitting mechanism.

The adjustment of the front wall 19 longitudinally of the machine is caused by adjusting longitudinally of the machine a member 240 (Fig. 3), said member being fast to the rear ends of two rods 243, 245 slideable, respectively, in bores in bosses which are integral with the stationary side plate 171, one of said bosses being shown at 249. The front wall 19, as will be described in detail later, is carried by two right-angled arms 269, 271 having spaced hubs which are rotatable respectively upon the slide rods and, together with the member 240, are continually urged to the left (Fig. 3) by compression springs 251, 253. The member 240, and with it the front wall 19, is adjusted toward the splitting mechanism against the force of the springs by a cam 255, which engages a small roll 257 carried by the member 240. The cam is rotatable about a stud 259 and is provided with a handle 261 by which it may be rotated, the handle being provided with a spring-pressed locking pin (not shown) having a conical end which enters holes 263 formed in a stationary part of the machine. The construction is such that by exerting a small force, the cam 255 may be turned, the pin serving to hold the cam securely enough when it enters any one of the holes so that the cam will not move until force is again exerted upon the handle 261.

In order to adjust the front wall 19 vertically (Fig. 8), this wall is pivoted, respectively, on the stems of screws 265, 267 to the ends of two parallel generally horizontal arms 269, 271, which are rotatable, respectively, about the slide-rods 243, 245. Each of these arms is bent at right angles

and, therefore, has a rearwardly extending portion. Referring to Fig. 2, wherein the rearwardly extending portion of the arm 269 is shown, this portion has two spaced hubs which encircle and are rotatable on the slide-rod 243. The lower arm 271 is shaped like the upper arm and similarly rotatable on the lower rod 245. As has been stated above, when the casting 240 is adjusted longitudinally of the machine, the slide-rods and the front wall 19 are adjusted with it. The pivot screws 265, 267 and the ends of the slide-rods 243, 245 (Fig. 8) form the corners of a rectangle, so that, if one of the arms 269, 271 is swung about its rod, the other will remain parallel to it, and the front wall 19 will be adjusted vertically. In the illustrated construction, the upper arm 269 is swung down by turning the knurled head 273 (Fig. 2) of a small shaft 275, which has at its other end an eccentric 277 (see also Fig. 8). The small shaft 273 is rotatably mounted in ears formed upon the rearward extension of the arm 269. If, therefore, the small rotatable shaft 275 is bodily raised or lowered, the arm 269 will be swung about the slide-rod 243. The small shaft 275 is urged bodily downward at all times by a spring 276 (Fig. 8), which acts to push down the rearward extension of the lower arm 271 and thereby to swing up the ends of the arms 271, 269 which are pivoted to the front wall 19. This tends, of course, to raise the front wall. In order to lower the front wall, the short shaft 275 is rotated so as to rotate the eccentric 277 on the end of the shaft. The eccentric is held down by the action of the spring, referred to above, against the end of a stop screw 281; and consequently, when the eccentric is turned, the small shaft 275 rises and falls bodily, the front wall 19 rising when the shaft is lowered and being lowered when the shaft rises. The small shaft 275 has an enlarged cylindrical portion next to the eccentric 277, which has in its periphery a series of small depressions 283 (Fig. 8) with which a catch in the form of a spring plunger cooperates.

The upper end of the feed arm 69 (Fig. 3) is connected by a link 291 with a carrier 293, which is horizontally slideable on two parallel rods, one of which is shown at 295, said slideable carrier having at its upper portion a longitudinally extending guide 297 having beveled edges. A slide block 299 has a dovetailed guideway on its underside to fit over the guide, the block 299 thus being adjustable longitudinally of the machine along the guide 297, the block being locked in adjusted position along the guide by a small clamp operated by a handle 301. The block 299 has in its upper side a dovetailed guideway running crosswise of the machine in which a cross slide 303 is slideable. Mounted upon this cross slide and extending longitudinally of the machine is a small narrow piece 305, the rear end of which is at a lower level than is the front end. On the rear end of this narrow piece is mounted a vertical roll 307; and to the forward end is fastened the pusher or feed slide 11 having projecting from its underside and integral with it a small spacing member 309. Two small screws 311 fasten the feed slide with its spacing member to the piece 305. The roll 307, the right-hand end of the piece 305 and the spacing member 309 extend up through a longitudinal slot 313 in a long bar 315, the forward end of this bar (Fig. 2) forming part of the bottom or table of the magazine. The rest of the bottom or table of the magazine is formed by two plates 317, 319 (Fig. 8) fastened to the bar

and having their upper faces flush with the upper face of the bar.

The bar 315 is adjustable crosswise of the machine and carries with it the rear wall 17 of the magazine in order to swing the rear end of the stack of blanks so as to provide for right and left blanks; and, when the bar is so adjusted, it also carries with it the feed slide 11 through the mechanism which has just been described. The bar is adjusted crosswise of the machine by swinging a lever 321 (Fig. 2), the hub of which is rotatable about a vertical stud 323 carried by the frame of the machine, one end of the bar being pivoted to the outer end of an arm 325 which is integral with the lever 321. The forward end of the bar 315 is pivoted at 327 to one end of an arm 329, the hub of which is pivoted about a vertical stud 331 carried by the frame of the machine. The bar 315 is thus pivotally supported upon the two arms 325, 329, and these arms, together with the studs 323, 331 about which they swing, form part of a parallel link motion, so that when the two arms are swung in unison the bar 315 moves crosswise of the machine. In order so to swing the hub of the arm 329 when the lever 321 is swung, said hub has integral with it a second arm 333; and the outer end of this arm is connected by a long link 335 with an extension of the lever 321. When, therefore, the lever 321 is swung about its vertical stud 323, the bar 315 and with it the bottom of the magazine is moved crosswise of the machine. Since the bar carries with it the rear wall 17 of the magazine which engages the rear ends of the sole blanks, the crosswise adjustment of this rear wall swings the rear end of the stack of sole blanks in one direction or the other, so as to provide for right and left blanks. In order to facilitate swinging the lever 321 and holding it in adjusted position, one end of this lever swings over a stationary member 337 provided with a curved slot 339, the center of curvature of which is the axis of the stud 323 about which the lever swings, a clamping screw 341 providing means for locking the lever in adjusted position. In order to be able to determine for any given stack of soles just how far in one direction or the other the lever 321 may swing, the stems of a V-shaped fork 343, one or the other branch of which engages a pin 344 on the lever 321, is mounted for sliding adjustment crosswise of the machine upon the head of the stud 323, said stem having a slot through which and into the stud passes the stem of a clamping screw 345.

As has been stated, the rear wall 17 of the magazine partakes of the crosswise adjustment of the bar 315. This rear wall is also slidably adjustable lengthwise of the bar. Referring to Fig. 3, the rear wall 17 is carried by a casting 347 which is slidable for a short distance lengthwise of the machine on the top of a block 349. The underside of the block has a guideway to fit over the bar 315 and is held on the bar by a plate 351, which extends across the underside of the bar and is fastened to the walls of the guideway. The block is thus slidable along the bar. In order to hold the block, and with it the rear wall 17 of the magazine, in any position to which it is moved forwardly, the bar has teeth 353 with which cooperate one or the other of two small pawls 355, one located slightly in advance of the other, said pawls being pivoted to the block and having upright stems acted upon by small horizontal spring-pressed plungers 357. In order to be able to release the pawls when it is desired to move the block rearward, a pusher 359, which may be

5 moved to act upon the upright stems of the pawls so as to release them, has a horizontal stem 361 slidably mounted in the block, the pusher being normally held in inoperative position by a compression spring 363.

10 Preparatory to operating upon sole blanks, these blanks are arranged in stacks, each stack containing sole blanks of the same length, all of which are either rights or lefts. The stacks 15 containing the longest blanks are preferably operated upon first, and then in order the stacks of successively shorter blanks. Before placing a 20 stack of blanks in the magazine, the pusher 359 is pushed forward to disengage the pawls 355 from the teeth 353, and the block 349, which carries the rear wall 17 of the magazine, is moved back. The handle 361 is manipulated to unlock the feed slide 11 from the guide 297, and the feed slide is moved back. The trigger 203 (Fig. 8) is manipulated to free the side walls 13, 15 and to 25 permit the springs 183, 191 to separate the side walls as far as possible. The front wall 19 of the magazine is adjusted lengthwise in accordance with the length of the sole blanks by manipulating the handle 261 (Fig. 3) and heightwise, in accordance with the thickness of the sole blanks, by turning the small shaft 275 (Fig. 8). The stack of sole blanks is now placed in the magazine; the side walls 13, 15 are moved toward each 30 other until they engage the opposite sides of the stack; and the block 349 is pushed forward, said block carrying with it the rear wall 17 of the magazine and the feed slide 11 until the toe ends of the sole blanks, except for the bottom one, engage the front wall 19 of the magazine. This is 35 the position shown in Fig. 3, in which the forward end of the stack of blanks is in contact with the front wall 19 and the feed slide 11 is substantially in contact with the rear end of the lowermost blank and ready to start its forward or feeding stroke. With this construction and in view of the fact that the extent of reciprocation of the feed slide is always the same and that the blanks of any given stack are always of the same length, each blank of every stack which is placed in the magazine is fed the same distance by the feed slide. Consequently, the lengthwise position of the blanks of the stack, which depends upon the position of the front wall 19, determines the locality longitudinally of each blank which will be engaged by the matrix.

40 As has been explained, the side walls 13, 15 (Fig. 8) are urged apart at all times by the coiled springs 183, 191 and are held in adjusted position by the small Horton clutch contained in the casting 201. A clutch of this kind always has a small amount of backlash, and consequently, when the side walls 13, 15 are moved up against opposite sides of the stack and released, they separate 45 slightly so that the sole blanks are free to settle down as the lowermost blanks of the stack are successively fed. The feed slide 11 is separate from the block 349 and is moved forward because the block contacts with the rear end of the slide when the block is moved forward. The rear wall 11, as has been explained, is rigid with the casting 347 (Fig. 3), which is slidable for a short distance lengthwise of the machine on the block 349. It is held normally at the rear limit of its 50 path by a spring-pressed plunger 364 (Fig. 2) which acts upon one arm of a bell crank lever 367, said bell crank lever being pivoted at 369 to the block 349. Near the end of that arm of the bell crank lever which is engaged by the spring-pressed plunger 364 is a cam slot through which

extends a pin 365, said pin being driven into the slideable casting 347. When the block 349 is pushed forward, this is accomplished by pushing upon the free end of the rear arm of the bell crank lever. The first effect of such pushing is to rotate the bell crank lever slightly, and thereby to move the casting 347, and with it the rear wall 17 of the magazine, slightly forward with respect to the block. The further effect of such pushing is to move forward the block 349 and the rear wall 17 of the magazine. This forward movement is continued, as has been stated, until the forward end of the stack contacts with the front wall 19 of the magazine. When this has been accomplished and the bell crank lever 367 is released, the casting 347 and with it the rear wall 17 of the magazine are moved slightly rearward by the spring-pressed plunger 364, the parts then being in the positions shown in Fig. 2. This backward movement of the rear wall 17 is very slight but is sufficient to prevent the sole blanks of the stack from being gripped between the rear wall 17 and the front wall 19 of the magazine and permits the stack to settle as the lowermost blanks are successively fed from it. After having thus placed a stack of blanks in the magazine, grain side up, and adjusted the walls as described above, the long bar 315 is adjusted crosswise of the machine, depending upon whether the blanks are rights or lefts, by swinging the lever 321 and locking it in position by means of the clamping screw 341. Such adjustment of the bar adjusts the rear wall 17 and the feed slide 11 with it. In Fig. 2, a stack of right sole blanks is shown, grain side up, in position to be fed.

As has been stated, there is provided a series of presser fingers for pressing the blanks against the matrix roll, there being forty-six of these fingers in the illustrated machine. As a blank passes between the rolls of the splitting mechanism and is split into an outsole and an insole, it is desirable that an increased pressure should be exerted upon that portion of the blank which engages the matrix, in order to distort the blank properly and force it firmly against the bottom of the matrix. To this end, the middle ones of the series of fingers, the four middle ones of the forty-six in the illustrated machine, are acted upon by springs which are much stronger than the springs which act upon the other presser fingers, and the stronger springs are permitted to be operative as a portion of each blank arrives in position to be forced into the matrix. Referring to Fig. 3, one of the four middle fingers is shown at 26, and one of the other forty-six at 526, the positions shown being those occupied when the machine is at rest. In Fig. 11, these fingers are shown on a larger scale, but it should be noted that in Fig. 11 the machine is not at rest. Instead, a sole is about to enter between the rolls. The fingers are all pivoted about a rod 371 and are individually urged to rotate in a counter-clockwise direction by springs. To this end, the tail of each finger has a small boss which is acted upon by a small horizontally slideable spring-pressed plunger; but the springs which act upon the plungers for the middle fingers 26 are stronger than the springs for the other plungers, and the operative ends of the four middle fingers 26 are capable of being swung farther in a counter-clockwise direction than are the operative ends of the other fingers. In Fig. 3, the two upper plungers 373 are associated with two of the middle fingers 26, while the two lower 75

plungers 375 are associated with two of the other fingers 526. Each plunger 375 is horizontally slideable through a bore in a wall of a small box-like member 377, which is fastened to the frame, each plunger having at its left-hand end a head which, when the machine is at rest or when no blank is being operated upon, is urged by a compression spring 379 to the limit of its movement to the right. When the plungers 375 are in this extreme right-hand position, as shown, the operative ends of the fingers 526 are substantially flush with the periphery of the toothed feed roll 21. The plungers 373, which act upon the middle fingers 26, are also horizontally slideable through bores in the wall of the box 377 and are acted upon by stronger springs, the construction being such that, when the machine is at rest, or when no blank is being operated upon, the operative ends of the fingers 26 are close to the matrix roll, as in Fig. 3. If these four strongly pressed fingers were allowed to remain in this position, they would tend to interfere with the entrance of the leading end of a blank between the rolls. Just before the leading end of a sole blank which is being fed reaches a position in which it would engage the middle fingers 26, these fingers are swung down by pressure exerted upon their tails to the position shown in Fig. 11 so as to permit the blank to enter readily between the rolls. In this position they are inoperative or substantially so. When, now, a portion of the blank is about to reach a position in which it should be forced into the leading end of the matrix, the pressure upon the tails of the fingers 26 is withdrawn, and the fingers are free to be caused by their strong springs to distort the blank and press it firmly into the matrix. They so press this portion of the blank into the matrix during that portion of the cut of the knife which produces the island on the sole and the corresponding opening in the insole. They continue to press upon the blank as long as it remains in the machine and are still in pressing position when it leaves the machine.

Referring now to Fig. 3, the mechanism for thus controlling the operation of the four middle fingers 26 will be described. Pivoted about the rod 371, about which all the fingers are pivoted, are the upper ends of two parallel arms, one of which is shown at 381. A short horizontal rod 383 connects the lower portions of these two arms and has mounted upon it a roll 385, which is just long enough so that when moved to the left it will engage the tails of the four middle fingers 26. Pivoted to the arms is one end of a link 387, the other end of which is pivoted to one arm of a bell crank lever 389 mounted to swing about a fixed pivot 391. At the extremity of the other arm of the bell crank lever is a roll 393. The pivot which connects the right-hand end of the link 387 with one arm of the bell crank lever 389 carries a roll 395 which runs on a generally cylindrical cam on the shaft 81, said cam having a projection 397; and, when the roll is engaged by the projection 397, this pivotal connection is pushed up past dead center. It is prevented from continuing its upward movement by contact of the roll 393 with the cylindrical portion of another small cam on the shaft 81, said small cam having a projection 399. The pushing up of the pivotal connection between the toggle links 387, 389, which causes the roll 385 to engage the tails of the four middle fingers 26 and swing them to the left, takes place, as shown in Fig. 11, just before the leading end of a blank 100, which is being fed from the magazine, would otherwise

engage these fingers. The operative ends of these middle fingers are thus moved away from the matrix roll to permit ready entrance of the leading end of a blank between the rolls. They remain in this inoperative position until the leading end of the matrix is about to engage the blank. They are then released by the projection 399 (Fig. 3) which engages the roll 393 and pulls down the knuckle of the toggle which comprises the link 387 and one arm of the bell crank lever 389. The 10 middle fingers 26 are thereafter operative and remain so until a succeeding blank is fed from the magazine, whereupon they are once more depressed for an interval. By the construction which has been described above, there is provided a splitting mechanism including a matrix member, a knife, a feed roll, presser fingers and means for increasing the pressure exerted by those fingers which engage the portion of a blank which is distorted and forced into the matrix. The purpose of the auxiliary presser fingers 29, which are carried by the underside of the stripper plate 31, is to ensure that the leading portion of the blank shall be properly held up against the matrix roll during the time that the operative ends of the middle fingers 26 are being held down. There are four of these auxiliary fingers, and they are located in line with the middle presser fingers 26.

Referring to Figs. 1 and 2, the soles and insoles which result from the splitting of the blanks pass, respectively, down a chute 33 and down the stripper plate 31 to a mechanism which delivers them into one or the other of two other receptacles. This delivering mechanism comprises two large disks, an upper disk 401 to receive the soles and a lower disk 403 to receive the insoles, said disks being fast to a vertical shaft 405 which is supported in bearings in a base 402 adjustably fastened to the frame of the machine. The shaft is rotated continuously in the direction indicated by the arrow (Fig. 2) by means of a pulley 407, which is fast to the shaft, and a belt 409 which passes around the pulley 407 and around a pulley 411 on the countershaft 81. Extending partly around the peripheries of the disks is a thin upright wall 412, which prevents the soles and insoles from being thrown off the disks until they reach the proper localities and aids in guiding the soles and insoles, respectively, into receptacles 413, 415. The soles are received upon the upper disk 401, the end of the wall 412, considered in a direction of rotation of the disk, which cooperates with this upper disk, being indicated at 417. After passing this end, the sole is free to be thrown from the disk. In order to guide the sole into the receptacle 413, a deflector 419 is provided. The hub of this deflector is pivoted about the upper end of the shaft 405 and is held in adjusted angular position by a bar 421, said bar being pivoted at one end about the upper end of a vertical rod 423 and having near its other end a slot 425. The stem of a clamping screw 427 passes loosely through the slot and is threaded into the deflector 419, so that the deflector may be held in angularly adjusted position about the axis of the vertical shaft 405. There are two other upright rods 428, 430 like the rod 423. All three of these rods are carried by the base 402 and support the wall 412 by passing through perforated ears or lugs which are fast to said wall. In Fig. 2, there is shown a sole 200 in the position which it occupies on the rotating disk 401, just before it is delivered into the receptacle 413. The lower rotating link 403 is a duplicate of the upper one and has associated with it a de-

15 flector 433 like the deflector 429 and held in adjusted position to cause the insoles to be delivered into the receptacle 415 by a bar 435, which is like the bar 421. The end portion of the wall 412, considered in the direction of the rotation of the disk which cooperates with the lower disk, is indicated at 422. An insole 300, which is about to be delivered into this chute, is shown in engagement with the deflector 433.

20 In the operation of the machine, a stack of sole blanks is placed upon the bottom of the magazine, and the side, front and rear walls of the magazine are adjusted in the manner which has been described above. The starting lever 131 (Fig. 1) is then swung to the right into contact with the stop 133. This throws in the clutch and starts the operation of the machine. The blanks are fed rapidly in succession to the splitting mechanism, where they are split into soles and insoles, these latter being received on the rotating disks 401, 403 and discharged, respectively, into the receptacles 413, 415.

25 The machine described above is provided with a matrix roll having a single matrix, which is adapted to be used with both right and left sole blanks; and, in order to cause such matrix to contact properly with either right or left blanks, the right blanks are presented to the roll at one angle and the left blanks at another, this being accomplished by adjusting crosswise of the machine the rear wall of the magazine which holds the stack of blanks. In Fig. 12, there is shown a modified construction. A roll 523 having two 30 matrices 524, 525, one for right sole blanks and one for lefts, together with a part of a left sole blank, is shown in position to have the blank fed to the roll, the line 527 indicating the path of travel of the blank as it is presented or fed to the roll. When right sole blanks are to be operated upon, the matrix roll 523 is adjusted to the right, until the matrix 524 is in the position which is occupied in the figure by the matrix 525.

35 The mounting of the matrix roll, in such manner that it may be so adjusted, is as follows. The arms 533, 535, which correspond to the arms 33, 35 of Fig. 6 and carry the matrix roll 523, are spaced apart far enough to permit horizontal adjustment of the roll, said roll being mounted, except for its capability of longitudinal adjustment, substantially as is the matrix roll of Fig. 6. The hub of the gear 595, which drives the matrix roll, is pinned to one end of a short shaft 555 rotatably mounted in the arm 533, the other end of said shaft being enlarged and having a wide 40 straight-sided groove passing diametrically through it to receive a projection on the matrix roll. From the bottom of the groove a bore extends into the center of the shaft and has driven into its wall a small pin 561. The roll shaft 563, having in its left-hand end a spiral groove 565 to receive the pin, is slidably and rotatably mounted in the other arm 535 and has a shoulder 566 which engages a boss on the matrix roll. The gear 595 is driven by a gear 596, which is like the gear 93 of Fig. 4, except that it is an elongated gear along which the gear 595 may be adjusted. With the parts in the positions shown in Fig. 12, the matrix roll 523 will remain in the longitudinal position shown, wherein the matrix 525 is properly located for operating upon left sole blanks. If, now, right sole blanks are to be operated upon, the gear 595, the short shaft 555 which is fast to the gear, the matrix roll 523 and the matrix roll shaft 563 are slid to the right 45 to bring the matrix 524 into the position occupied

in the figure by the matrix 525. This sliding adjustment is by swinging a hand lever 597 pivoted about a fixed shaft 599 and having at its upper end a roll 601, which extends into a groove formed in the hub of the gear 595. The hand lever 597 may be held in either of its two angular positions by a spring-pressed plunger 603 which enters one or the other of two holes in a stationary plate 605, one hole being shown at 607.

It will be noted by reference to Fig. 11 that the edge of the knife 27 is spaced somewhat back of a plane passed through the axes of rotation of the rolls 21, 23, that is from the bite of the rolls. It is desirable that the edge of the knife be located as close as is possible to said bite and still allow for clearance of the work. In the present case, as is usual, the edge is located in a plane passed through the axis of the upper roll substantially at right angles to the surface of the knife adjacent to its edge. The operative portions of the middle presser fingers 26, the group which acts to force a part of the work into the matrix, are located, when they are in raised operative position, above the corresponding portions of the other fingers 526, the group which acts to press other parts of the work against the cylindrical portion of the matrix roll. The operative portions of the fingers 26 are also spaced farther from the edge of the knife than are the operative portions of the fingers 526; their operative portions are rounded and a plane passed through the axes of the rolls intersects these rounded portions. The operative ends of the fingers 526 lie close to the edge of the knife. It is necessary that the cutting of sole blanks be done accurately. For example it is commonly a requisite that the variation in thickness of that part of the blank which is split by a cut parallel to a face of the blank shall not exceed .005 of an inch. With the construction of the present machine, the fingers 26 bend a part of the moving blank into the matrix in such manner that the knife enters and leaves the blank properly, and at the same time the fingers 526 hold other portions of the blank firmly against the cylindrical surface of the roll close to the edge of the knife so that the thickness of that portion of the blank which is split on the cylindrical portion of the roll is of a uniform thickness.

Although the invention has been set forth as embodied in an illustrated machine, it should be understood that the invention is not limited in the scope of its application to the particular machine which has been shown and described.

Having thus described my invention, what I claim as new and desire to secure by Letters Patent of the United States is:

1. A machine of the class described having, in combination, a roll having a cylindrical portion and a matrix, a straight-edged knife adapted to cooperate with the cylindrical portion to split that part of the blank which engages the cylindrical portion by a cut which is parallel to a face of the blank and to cooperate with the matrix to make in that part of the blank which engages the matrix a cut which is at an angle to the first-named cut, a feed roll, a series of presser fingers adapted to press a part of the moving blank against the cylindrical portion and another part against the matrix, and means constructed and arranged to compel certain presser fingers which cooperate with the matrix to exert a greater pressure upon the blank than do other fingers which cooperate with the cylindrical portion.

2. A machine for cutting a sole-shaped blank into an outsole having a projection on its forepart and an insole having a similarly located opening, said machine having, in combination, a matrix 5 roll having a cylindrical portion and a matrix surrounded by said cylindrical portion, a knife adapted to cooperate with the cylindrical portion to split that part of the blank which engages the cylindrical portion by a cut which is parallel 10 to a face of the blank and to cooperate with the matrix to produce the projection on the outsole and the corresponding opening in the insole, a feed roll, and a series of yielding presser fingers constructed and arranged to press a part of the 15 moving blank against the cylindrical portion of the matrix roll with a given pressure and another part into the matrix with a greater pressure.
3. A machine of the class described having, in combination, a knife, a member having a matrix, a cooperating member, a plurality of presser fingers for pressing the blank against the matrix member, yielding means tending at all times to urge the fingers into operative position, and automatically operated means for moving selected fingers 20 away from operative position and for holding them thus to facilitate the entrance of the leading end of a blank between the members and for thereafter releasing them.
4. A machine of the class described having, in combination, a knife, a pair of rolls which cooperate with the knife, a plurality of presser fingers for pressing a moving blank against one of the rolls, springs for actuating the presser fingers, one of the springs being stronger than others, and 25 means for moving the operative end of a finger which is actuated by the stronger spring away from that roll against which the blank is pressed by the fingers to facilitate the entrance of the leading end of a blank between the rolls and for thereafter releasing the finger.
5. A machine of the class described having, in combination, a knife, a pair of rolls for feeding a blank to the knife, a plurality of presser fingers for pressing the blank against one of the 30 rolls, yielding means tending at all times to urge the fingers into operative position, and automatically operated means for moving the fingers away from operative position and for holding them thus to facilitate the entrance of the leading end of a blank between the rolls and for thereafter releasing them.
6. A machine of the class described having, in combination, a knife, a matrix roll, a cooperating roll, a plurality of yielding presser fingers for 35 pressing a moving blank against the matrix roll close to the edge of the knife, the fingers which cooperate with the matrix being adapted normally to occupy a position nearer to the matrix roll than the other fingers, and automatically operated means for moving said matrix fingers away from the matrix roll, for holding them in the position to which they are moved so as to facilitate the entrance of the leading end of a blank between the rolls, and for thereafter releasing them.
7. A machine of the class described having, in combination, a knife, a roll having a cylindrical portion and a matrix, a cooperating roll, a plurality of yielding presser fingers for pressing a 40 moving blank against the matrix roll close to the edge of the knife, means for causing certain of the fingers which cooperate with the matrix to exert a greater pressure upon the blank than the others, the operative ends of the fingers which cooperate with the matrix being adapted, when
- 75

permitted, to occupy a position nearer to the matrix roll than the other fingers, means for moving said matrix fingers away from the matrix roll, for holding them in the position to which they are moved so as to facilitate the entrance of the leading end of a blank between the rolls, and for thereafter releasing them, and auxiliary presser fingers located in advance of the matrix fingers for holding the leading end of the blank against the matrix roll while the matrix fingers are in their position away from said roll.

3. A machine of the class described having, in combination, mechanism including a knife and a pair of cooperating rolls for operating upon blanks, a plurality of fingers for pressing a moving blank against one of the rolls, said fingers being held from movement with the blank, means for feeding blanks in succession to the bite of the rolls over the operative ends of the fingers, and mechanism independent of the blank and operating in timed relation with the feeding of a blank for depressing and then releasing certain of the fingers.

9. A machine of the class described having, in combination, mechanism including a knife and a pair of cooperating rolls for operating upon blanks, a plurality of fingers for pressing a moving blank against one of the rolls, means for feeding blanks in succession to the bite of the rolls over the operative ends of the fingers, mechanism operating in timed relation with the feeding of a blank for depressing and then releasing certain of the fingers, and auxiliary presser fingers located in advance of the fingers which are depressed for holding the leading end of the blank against one of the rolls.

10. A machine of the class described having, in combination, a matrix roll, a cooperating roll, a knife, presser fingers, yielding means tending at all times to move the fingers into position to press a portion of the moving blank into the matrix, a rotating shaft, and means operated by the shaft for moving the fingers away from the matrix roll, for holding them thus for an interval and for thereafter releasing them.

11. A machine of the class described having, in combination, mechanism including a matrix for operating upon blanks, a magazine for a stack of blanks, said magazine having a front wall, means for feeding blanks in succession beneath said wall to the operating mechanism, an arm pivoted about a substantially horizontal axis and pivoted at its free end to the front wall whereby, when the arm is swung about its axis, the front wall is adjusted vertically, said arm, and with it the front wall, being adjustable toward and from the operating mechanism.

12. A machine of the class described having, in combination, mechanism including a matrix for operating upon blanks, a magazine for a stack of blanks, said magazine including a front wall, means for feeding blanks in succession beneath said wall to the operating mechanism, a pair of parallel arms pivoted about substantially horizontal axes and forming part of a parallel link motion, said arms being pivoted at their free ends to the front wall whereby, when the arms are swung, the front wall is adjusted vertically, said arms, and with them the front wall, being adjustable toward and from the operating mechanism.

13. A machine of the class described having, in combination, mechanism including a matrix for operating upon blanks, a magazine for a stack of blanks, said magazine including a front wall, means for feeding blanks in succession beneath

said wall, a pair of rods slidable longitudinally of the machine, a pair of arms each pivoted about the axis of one of the rods and pivoted at their free ends to the front wall, means for swinging the arms about the axes of the rods to adjust the front wall vertically, and means for adjusting said rods, and with them the pivoted arms and the front wall, toward and from the operating mechanism.

10 14. A machine of the class described having, in combination, mechanism including a symmetrical matrix, a magazine for a stack of blanks, a feed member for feeding blanks in succession from the magazine to the operating mechanism, and means whereby a part of the magazine may be adjusted to change the angular position of the stack according to whether the blanks to be fed to the operating mechanism are rights or lefts.

20 15. A machine of the class described having, in combination, mechanism for operating upon blanks, said mechanism including a symmetrical matrix, a magazine for a stack of blanks, a feed member for feeding blanks in succession from the magazine to the operating mechanism, and means whereby a part of the magazine may be adjusted to change the angular position of the stack and the location of the path of travel of the feed member according to whether the blanks to be fed to the operating mechanism are rights or lefts.

30 16. A machine of the class described having, in combination, mechanism for operating upon blanks, said mechanism including a matrix roll having a symmetrical matrix, a magazine for stacks of blanks, a feed member for feeding blanks in succession from the magazine to the operating mechanism, said magazine having a rear wall, and means whereby the rear wall may be adjusted crosswise of the machine to change the angular position of the stack according to whether the blanks to be fed to the operating mechanism are rights or lefts.

40 17. A machine of the class described having, in combination, mechanism for operating upon blanks, said mechanism including a matrix roll having a symmetrical matrix, a magazine for stacks of blanks, a feed member for feeding blanks in succession from the magazine to the operating mechanism, said magazine having a rear wall, and means whereby the rear wall may be adjusted crosswise of the machine to change the angular position of the stack and the location of the feed member according to whether the blanks to be fed to the operating mechanism are rights or lefts.

50 18. A machine of the class described having, in combination, mechanism for operating upon blanks, a magazine for a stack of blanks to be operated upon, and means for feeding blanks in succession to the operating mechanism, said magazine including two side walls for engaging the sides of the stack, yielding means continually urging said walls to separate and means for holding them in any position of approach to which they may be moved.

60 19. A machine of the class described having, in combination, mechanism for operating upon blanks, a magazine for a stack of blanks to be operated upon, and means for feeding blanks in succession to the operating mechanism, said magazine including two side walls for engaging the sides of the stack, yielding means continually urging said walls to separate, means for holding them in any position of approach to which they

may be moved and means for releasing them whereupon they are moved farther apart.

20. A machine of the class described having, in combination, mechanism for operating upon blanks, a magazine for a stack of blanks to be operated upon, and means for feeding blanks in succession to the operating mechanism, said magazine including two side walls for engaging the sides of the stack, yielding means continually urging said walls to separate, means for holding them in any position of approach to which they may be moved, and means for adjusting said walls in unison crosswise of the machine.

21. A machine of the class described having, in combination, mechanism including a matrix for operating upon blanks, a magazine for holding stacks of blanks, the blanks of any given stack being all of the same length but the blanks of different stacks being of different lengths, said magazine having a front wall adjustable toward and from the operating mechanism to vary the distance of the leading ends of the blanks of the stacks from the operating mechanism, means including a feed member for feeding blanks in succession from the stacks to the operating mechanism, said means being constructed and arranged to feed all blanks the same distance irrespective of their lengths, said magazine having a rear wall adjustable toward and from the front wall, and means whereby adjusting the rear wall toward the front wall adjusts the feed member with it.

22. A machine of the class described having, in combination, mechanism including a matrix for operating upon blanks, a magazine for holding stacks of blanks, said magazine having a front wall and a rear wall, a member for feeding blanks in succession from the stack to the operating mechanism, means for reciprocating said member in a path of fixed length, means whereby the front wall of the magazine may be adjusted toward and from the operating mechanism, and means whereby the rear wall may be adjusted toward the front wall, the construction being such that adjusting the rear wall toward the front wall adjusts the feed member with it.

23. A machine of the class described having, in combination, mechanism including a matrix for operating upon blanks, a magazine for holding stacks of blanks, said magazine having a front wall and a rear wall, a member for feeding blanks in succession from the stack to the operating mechanism, means for reciprocating said member in a path of fixed length, means whereby the front wall of the magazine may be adjusted toward and from the operating mechanism, said rear wall being adjustable toward the front wall, and means whereby adjustment of the rear wall toward the front wall adjusts the feed member so that it is substantially in contact in succession with the trailing ends of the blanks of a stack when it begins its feeding movement irrespective of the adjusted position occupied by the front wall.

24. A machine of the class described having, in combination, mechanism including a matrix for operating upon blanks, a magazine for a stack of blanks, a bar which is held from movement during the feeding of the blanks, a member for feeding blanks in succession to the operating mechanism, said member being slidably mounted for reciprocation on the bar, means whereby the bar, and with it the feed member, may be adjusted crosswise of the machine, and means for reciprocating the feed member on the bar once

for each blank fed to the operating mechanism.

25. A machine of the class described having, in combination, mechanism including a matrix for operating upon blanks, a magazine for a stack of blanks, said magazine including a front wall and a rear wall, a support for the rear wall mounted for sliding movement toward and from the front wall, a member for feeding blanks in succession from the stack to the operating mechanism, a reciprocating carrier for said feed member with respect to which the feed member is slidably adjustable toward and from the front wall, the feed member being in the path of forward sliding movement of the support for the rear wall, whereby when the support is adjusted forward to move the rear wall into operative relation to the rear end of the stack, the feed member is adjusted with respect to its carrier.

26. A machine of the class described having, in combination, mechanism including a matrix roll for operating upon blanks, spaced aligned bearings between which said roll is located, a hollow driving shaft rotatable in one of the bearings, there being a driving connection between one end of the driving shaft and the adjacent end of the roll, a pin projecting into the hollow of the driving shaft, and a roll shaft extending through the other bearing, through the roll and into the hollow of the driving shaft, said roll shaft having a groove to receive said pin.

27. A machine of the class described having, in combination, mechanism including a matrix roll for operating upon blanks, spaced aligned bearings between which said roll is located, a hollow driving shaft rotatable in one of the bearings, there being between one end of the driving shaft and the adjacent end of the roll a driving connection which permits the roll to be slid into place, a pin projecting into the hollow of the driving shaft, and a roll shaft extending through the other bearing, through the roll and into the hollow of the driving shaft, said roll shaft having a groove to receive said pin.

28. A machine of the class described having, in combination, mechanism for operating upon blanks, said mechanism including a matrix roll having two matrices spaced longitudinally thereof and means for rotating the roll, said roll being longitudinally adjustable to bring either matrix into operative position.

29. A machine of the class described having, in combination, mechanism for operating upon blanks, a magazine for stacks of blanks, a feed member for feeding blanks in succession from the magazine to the operating mechanism, said magazine having a rear wall, and means whereby the rear wall may be adjusted crosswise of the machine to change the angular position of the stack and the location of the feed member.

30. A machine of the class described having, in combination, mechanism for operating upon blanks, a magazine for a stack of blanks, a bar which is held from movement during the feeding of the blanks, a member for feeding blanks in succession to the operating mechanism, said member being slidably mounted for reciprocation on the bar, means whereby the bar, and with it the feed member, may be adjusted crosswise of the machine, and means for reciprocating the feed member on the bar once for each blank fed to the operating mechanism.

31. A machine of the class described having, in combination, mechanism including a matrix for operating upon blanks, a magazine for holding a stack of blanks, the front wall of the maga-

zine being adjustable toward and from the operating mechanism to vary the distance of the leading ends of the blanks of the stack from the operating mechanism, a casting by which the rear wall of the magazine is carried, a block on which the casting is slidably, yielding means for normally holding the casting at the rear limit of its sliding movement on the block, said block being adjustable toward the rear end of the stack, a feed member in the path of adjustment of the block, and a member for adjusting the casting, the block and the feed member toward the rear end of the stack, said member when pushed toward the rear of the stack acting first to slide the casting a short distance on the block in opposition to the yielding means and then to move the casting, the block and the feed member until the rear wall of the magazine contacts with the rear end of the stack whereupon upon release of said member the yielding means acts to move the rear wall of the magazine slightly away from the rear end of the stack so as to permit the blanks of the stack to settle as the lowermost blanks are fed from it.

32. A machine of the class described having in combination, a roll having a cylindrical portion and a matrix, a knife adapted to cooperate with the cylindrical portion to split that part of the blank which engages the cylindrical portion by a cut which is parallel to a face of the blank and to cooperate with the matrix to make in that part of the blank which engages the matrix a cut which is at an angle to the first-named cut, a feed roll, and a series of presser fingers comprising a group adapted to press a part of the moving blank against the matrix and another group adapted to press another part of the blank against the cylindrical portion, the operative portions of the members of the first group being spaced a given distance from the edge of the knife and the operative portions of the members of the second group being located closer to the edge of the knife than are the operative portions of the first group.

33. A machine of the class described having in combination, a roll having a cylindrical portion

and a matrix, a knife adapted to cooperate with the cylindrical portion to split that part of the blank which engages the cylindrical portion by a cut which is parallel to a face of the blank and to cooperate with the matrix to make in that part of the blank which engages the matrix a cut which is at an angle to the first-named cut, a feed roll, and a series of presser fingers comprising a group adapted to press a part of the moving blank against the matrix and another group adapted to press another part of the blank against the cylindrical portion, the operative portions of the members of the first group being spaced a given distance from the edge of the knife and having rounded operative portions and the operative portions of the members of the second group being located closer to the edge of the knife than are the operative portions of the first group.

34. A machine of the class described having in combination, a roll having a cylindrical portion and a matrix, a feed roll, a knife, and a series of yieldable presser fingers comprising a group adapted to cooperate with the cylindrical portion of the roll and a second group adapted to cooperate with the matrix, the operative ends of the fingers of the first group being located close to the edge of the knife and the operative portions of the fingers of the matrix group being located farther from the edge of the knife.

35. A machine of the class described having in combination, a roll having a cylindrical portion and a matrix, a feed roll, a knife, and a series of yieldable presser fingers comprising a group adapted to cooperate with the cylindrical portion of the roll and a second group having rounded portions adapted to cooperate with the matrix, the operative ends of the fingers of the first group being located close to the edge of the knife and the operative portions of the fingers of the matrix group being located farther from the edge of the knife and so located that their rounded portions are intersected by a plane passed through the axes of the rolls.
